UNITED STATES PATENT OFFICE

2,124,429

PAD HOLDER

Parker J. O'Brien, Brooklyn, N. Y., assignor of
one-half to John G. Merrow, New York, N. Y.

Application April 10, 1937, Serial No. 136,139

4 Claims. (Cl. 15—209)

This invention relates to devices for detachably coupling pad and puff bodies in connection therewith to form a handle or supporting member therefor in the use of the pads or other bodies, and particularly in the supporting of scouring or cleansing pads composed of woven wire, steel wool and similar materials; and the object of the invention is to provide a holder for body members or pads of the class described having means in the form of a U-shaped clip adapted to be threaded through a part of the pad in coupling the same with a handle member; a further object being to provide a clip or coupling means for devices of the class described, which is arc-shaped in form so as to draw the pad in engagement with the holder in the operation of coupling the pad therewith; a still further object being to provide a holder or handle member having a chamber or recess, in the lower surface thereof, through which the U-shaped clip or the side arms thereof is adapted to pass, said arms being disposed within the boundaries of the recess in said member; a still further object being to provide means for spreading the pointed ends of the arms of said clip to aid in retaining the clip against displacement from said member; and with these and other objects in view the invention consists in a device of the class and for the purpose specified which is simple in construction, efficient in use and which is constructed as hereinafter described and claimed.

The invention is fully disclosed in the following specification, of which the accompanying drawings form a part, in which the separate parts of my improvement are designated by suitable reference characters in each of the views, and in which:

Fig. 1 is a side and sectional view of a device made according to my invention, illustrating one method of its use.

Fig. 2 is a plan view of the structure shown in Fig. 1 illustrating a coupling clip which I employ in detached position.

Fig. 3 is a bottom plan view of the structure shown in Fig. 1 with part of the construction broken away; and

Fig. 4 is a perspective view showing another use of the device.

In practice, I provide a supporting body or handle member 5 which is preferably composed of a non-metallic material, especially when used in conjunction with scouring pads, sponges and the like but which may be composed of any desired material when used in conjunction with

puffs or other applicators, which are not subjected to moisture in the use thereof.

The body 5 is in the form of a disk having a recess 6 in the lower surface thereof to form a peripheral downwardly extending flange 7, and centrally of the upper end of the body 5 is a knob or other finger piece 8 facilitating the grasping of the device, by the hand, in the use thereof.

One side of the body 5 is provided with a pair 10 of small downwardly extending apertures 9, in which is adapted to be mounted a coupling clip 10, substantially U-shaped in form, that is to say, the clip is provided with a narrow cross head 11 at its outer end and with curved arms 12 extending from the ends of the cross head and being flared outwardly in the direction of the free pointed ends 13 thereof, as clearly seen in Fig. 2 of the drawing.

The arms 12 of the clip or coupling member 20 10 are adapted to be moved together in their passage through the apertures 9, and said arms extend across the central portion of the U-shaped recess 6 and the pointed ends 13 are adapted to enter outwardly flared recesses 14 in the bottom wall of the recess 6, as clearly seen in Figs. 1 and 3 of the drawing. By outwardly flaring the recesses 14, the pointed ends 13 of the arms 12 will be flexed outwardly to aid in securing the clip 10 against displacement from the body 5. 30

When the clip is in its innermost position the cross head 11 thereof is disposed in close proximity to the other surface of the body 5, preferably at the corner portions 15 thereof, so as not to form an objectionable projection, while at the same time facilitating the grasping thereof, in the operation of removing the clip for the removal of a worn out pad or other element 16, and in the operation of coupling another pad therewith.

In Figs. 1, 2 and 3 of the drawing, 16 represents a pad of steel wool or similar material, whereas in Fig. 4 of the drawing, I have indicated at 16a a pad or sponge of woven wire. In this connection, it will be understood that any kind or class of element 16—16a may be attached to the body 5 depending entirely upon the use to which the device is to be applied, for example, a powder puff or an ordinary sponge, rubber pad or rubber sponge and similar elements may be applied. It will also be understood, in this connection, that the size of the body 5 may be varied and modified to suit the different uses.

In coupling the element with the body 5, the same is simply placed over the recess 6 and pressed 55

into this recess by the hand and the clip 10 is moved from the position indicated in dotted lines in Fig. 1 to the full line position, in which operation the curved arms 12 will pass into and through that part of the body of the element arranged in 5 the recess, and will have a tendency to draw this material inwardly into the recess to firmly retain the element against displacement from the body 5.

Upon consideration of Fig. 1 of the drawing, it 10 will be understood that the arms 12 are arranged within the boundaries of the recess 6 or, in other words, inwardly of the lower edge of the flange 7 so that these arms will not contact a surface over 15 which the device is moved should the element be come worn sufficiently to expose said arms.

In using the device in connection with steel wool, it will be apparent that after a pad or sponge of this material of a premanufactured form has become worn to some degree, the same may be 20 temporarily detached and folded or piled together in a smaller body and then recoupled with the holder, in this way no real waste will be experienced.

By employing a holder or handle member of the 25 class described with a simple and economical form of clip or coupling member, a very practical and useful means is provided for utilizing various kinds of cleansing sponges or pads as well as applicators. It will also be apparent that the clip 30 extends through a relatively wide or large area of the pad or other element, and this will serve to support the element 16 in close proximity to the lower edge of the flange 7, as clearly illustrated in Fig. 1 of the drawing.

Having fully described my invention what I 35 claim as new and desire to secure by Letters Patent, is:—

1. A handle member or mounting for cleaning pads and similar elements, said member comprising a large circular disc having a reduced knob or finger piece centrally of its upper surface, said disc having a large shallow recess in the lower surface thereof, a clip comprising a U-shaped member consisting of a crosshead and elongated curved side arms, the curvature of said 45 side arms being convex with respect to the bottom wall of said recess, and said arms being slidably supported in an edge of said disc and adapted to move transversely of said recess to engage a cleaning pad arranged in said recess and to retain said pad against displacement from said disc.

2. A handle member or mounting for cleaning

pads and similar elements, said member comprising a large circular disc having a reduced knob or finger piece centrally of the upper surface, said disc having a large shallow recess in the lower surface thereof, a clip comprising a U-shaped member consisting of a crosshead and elongated curved side arms, the curvature of said side arms being convex with respect to the bottom wall of said recess, said arms being slidably supported in an edge of said disc and adapted to move transversely of said recess to engage a cleaning pad arranged in said recess and to retain said pad against displacement from said disc, said arms flaring outwardly with respect to said crosshead, and the free ends thereof being pointed. 10 15

3. A handle member or mounting for cleaning pads and similar elements, said member comprising a large circular disc having a reduced knob or finger piece centrally of its upper surface, said disc having a large shallow recess in the lower 20 surface thereof, a clip comprising a U-shaped member consisting of a crosshead and elongated curved side arms, the curvature of said side arms being convex with respect to the bottom wall of said recess, said arms being slidably supported in an edge of said disc and adapted to move transversely of said recess to engage a cleaning pad arranged in said recess and to retain said pad against displacement from said disc, and said disc having sockets receiving the free ends of said 25 arms when the said arms are in pad retaining position.

4. A handle member or mounting for cleaning pads and similar elements, said member comprising a large circular disc having a reduced knob or finger piece centrally of its upper surface, said disc having a large shallow recess in the lower surface thereof, a clip comprising a U-shaped member consisting of a crosshead and elongated curved side arms, the curvature of said side arms being convex with respect to the bottom wall of said recess, said arms being slidably supported in an edge of said disc and adapted to move transversely of said recess to engage a cleaning pad arranged in said recess and to retain said pad against displacement from said disc, said disc having sockets receiving the free ends of said arms 40 when the said arms are in pad retaining position, and said sockets being in diverging relationship to each other so as to spread the ends of the arms 45 in entering said sockets. 50
